DESIGN FOR A POWDER SAMPLE DISPENSER

Nathaniel H. Freeman, New York, N. Y., assignor
to Elizabeth Arden Sales Corporation, New
York, N. Y., a corporation of Delaware

Application September 13, 1943, Serial No. 111,119

Term of patent 7 years

To all whom it may concern:

Be it known that I, Nathaniel H. Freeman, a citizen of the United States of America, residing in New York city, county of New York, and State of New York, have invented a new, original, and ornamental Design for a Powder Sample Dispenser, of which the following is a specification, reference being had to the accompanying drawing, forming part thereof, wherein:

Figure 1 is a front elevational view of a powder sample dispenser, showing my new design;
Figure 2 is a side elevational view; and
Figure 3 is a rear elevational view thereof.

I claim:

The ornamental design for a powder sample dispenser, substantially as shown.

NATHANIEL H. FREEMAN.
